MUD GUARD FOR SHOE HEELS

Richard C. Vogt, West New York, N. J.

Application February 14, 1931. Serial No. 515,772

5 Claims. (Cl. 36—7.3)

An important object of the present invention is to provide a satisfactory combination of an overshoе of open back, heelless form, and a mud guard carried by the overshoе and formed to embrace the shoe heel, protect the back of the shoe and stocking from mud splashes and also assist in holding the overshoе on the shoe.

Other objects of the invention will appear hereinafter.

10 In the drawing, Fig. 1 is a side view partly in section of the combined overshoе and heel mud guard applied to a ladies' high heel shoe, the shoe being indicated by dot and dash lines; and Fig. 2 is a section on the line 2—2 of Fig. 1. 15 The heel mud guard is shown in combination with a ladies' rubber overshoе of sandal form shaped to cover the toe portion only of the shoe, leaving the back portion of the shoe enclosing the heel of the wearer exposed. The upper 1 of said overshoе has its rear edges meeting the sole of the overshoе at a point materially in advance of the high heel of the shoe S indicated by dot and dash lines. An ankle strap 2 is formed with the upper. The sole 3 of the overshoе has a flexible 20 extension 4 to reach rearward along the under surface of the sole of the shoe S to the heel of the shoe and downward in front of the heel. Said extension may be formed integrally with the sole of the overshoе, of rubber or rubber composition. 25 At its rear end the extension carries the mud guard 5.

The mud guard is preferably made of rather soft, elastic rubber or rubber composition and it may be formed integrally with the sole extension 35 4 or affixed thereto. It comprises an elastic sleeve 6 and a mud guard flange 7. The sleeve is of material depth and at the side and back it tapers downward both inside and outside. Its front is formed by a straight elastic web 8 materially thinner and more easily stretchable than the remainder of the sleeve and merges into the sole extension 4. The flange 7 of the mud guard is integrally formed on the upper end of the sleeve and extends materially rearward from it and laterally 40 outward to a less degree from the opposite sides of the sleeve. The upper surface of the flange inclines outward and downward at opposite sides of the sleeve and at the rear it curves slightly downward and outward from the sleeve. The under surface of the flange is curved and concave, as indicated at 9. From its outer edge inward the sleeve is gradually thickened from its lower end upward and has its outer surface curved to merge with the under surface of the flange. 50 The sole extension 4 is freely flexible independ-

ently of the upper of the overshoе and permits the overshoе to be placed on the shoe by first putting on the body of the overshoе and then forcing the mud guard on the heel. The aperture of the mud guard is normally smaller than the heel so that 60 the guard must be expanded to apply it. When applied the guard grips the heel and, through the sole extension, assists in holding on the overshoе. If the strap 2 should slip down the overshoе will be held on by the mud guard. The overshoе is 65 readily removable by grasping the strong flange of the mud guard to first pull off the guard, and then removing the body of the overshoе.

The flange of the mud guard effectually protects the back of the shoe and the stocking from mud 70 splashes and the deep sleeve covers and protects the heel below the flange. The mud guard is also designed to present a neat, smart appearance.

What I claim is:

1. In combination, a heelless overshoе having 75 an upper open at the back and with its rear edges meeting the sole at a point in advance of the position of the shoe heel, the sole of the overshoе having an extension reaching rearward from said meeting point and flexible independently of the 80 upper; and a mud guard carried by said sole extension at the rear end thereof and formed to embrace the shoe heel and shaped to form a rearwardly and laterally projecting mud guard flange extending around the back and sides of the shoe 85 heel.

2. In combination, a heelless overshoе having 90 an upper open at the back and with its rear edges meeting the sole at a point in advance of the position of the shoe heel, the sole of the overshoе having an extension reaching rearward from said meeting point and flexible independently of the 95 upper; and a mud guard carried by said sole extension at the rear end thereof and comprising an elastic sleeve of material depth fittable around the shoe heel and having a rearwardly and laterally projecting mud guard flange extending around the back and sides thereof.

3. An overshoе comprising a heelless body to 100 cover the toe portion of the shoe and open at the back to leave the back portion of the shoe upper enclosing the heel of the wearer exposed, and a mud guard carried by the overshoе body and flexibly joined thereto and comprising an elastic 105 socket-like part to embrace and frictionally grip the heel of the shoe and assist in holding on the body of the overshoе and shaped to form a mud guard flange below said exposed back portion of the shoe upper and disposed to project rearwardly 110

and laterally away from the shoe at the back and sides of the mud guard.

4. An overshoe comprising a heelless body formed to cover the toe portion of the shoe and open at the back to leave the back portion of the shoe upper enclosing the heel of the wearer exposed, and a mud guard carried by the overshoe and forming an extension integral with the sole of the overshoe and comprising an elastic socket-like part to embrace and frictionally grip the heel of the shoe and assist in holding on the body of the overshoe and shaped to form a mud guard flange below said exposed back portion of the shoe and disposed to project rearwardly and later-

15

ally away from the shoe at the back and sides of the mud guard.

5. An overshoe comprising a heelless body to cover the toe portion of the shoe and open at the back to leave the back portion of the shoe upper enclosing the heel of the wearer exposed, and a mud guard carried by the overshoe body and flexibly jointed thereto and comprising an elastic sleeve to embrace and frictionally grip the heel of the shoe and assist in holding on the body of the overshoe and having at the top of said sleeve a mud guard flange disposed to project rearward away from the shoe.
